SIGNALING SYSTEM FOR RAILROADS

Filed July 11, 1930

UNITED STATES PATENT OFFICE

SEDGWICK N. WIGHT, OF ROCHESTER, NEW YORK, ASSIGNOR TO GENERAL RAILWAY SIGNAL COMPANY, OF ROCHESTER, NEW YORK

SIGNALING SYSTEM FOR RAILROADS

Application filed July 11, 1930. Serial No. 467,223.

This invention relates to automatic block signaling systems for single track railroads of the type commonly known as an absolute-permissive-block system, and more particularly to an improvement in the signaling circuits at a passing siding to provide what is commonly known as a double distant or caution indication for opposing trains approaching a passing siding.

10 One form of an absolute-permissive-block signaling system, of the type to which the present invention relates, is shown and described in detail in my prior Patent No. 1,294,736, dated February 18, 1919; and as 15 disclosed in this patent, a special control is provided for the signal, conveniently termed the approach signal, located at a distance from the end of a passing siding and governing train movement toward the 20 siding, so that this approach signal indicates caution when an opposing train is approaching the other end of a siding. As disclosed in my prior patent, this desired special control of the approach signal is obtained by an extra line wire extending the 25 length of the passing siding.

In accordance with the present invention, it is proposed to obtain the desired control of the approach signal for a passing siding, 30 without employing an additional line wire at the siding, by imposing an additional distinctive control upon the usual signal or line circuit extending the length of the siding, thereby eliminating the additional line 35 wire ordinarily required for the double distant control of the approach signal.

More specifically, in accordance with the present invention, provisions are made for energizing the home relay line circuit at a 40 passing siding with currents of different intensities as well as different polarities, so as to transmit over this line circuit an additional control which may be employed for obtaining the double distant indication of 45 the approach signal.

The characteristic features, objects, and advantages of the invention will be in part apparent, and in part pointed out, as the description progresses.

50 The accompanying drawing illustrates in

a simplified and diagrammatic manner one specific embodiment of the invention applied to a typical A. P. B. system of the type disclosed in my prior patent, above mentioned.

This drawing illustrates only part of the 55 complete A. P. B. system, many of the relays and circuits having been omitted to simplify the illustration. It will be readily apparent to those skilled in the art how the principles and features of the invention, 60 illustrated in this drawing, may be extended and incorporated with other relays and circuits not shown, so as to provide a complete signaling system for single track railroads.

The stretch of track adjacent the passing 65 siding PS is divided by insulated joints into track circuit sections in the usual way, each having a track battery and a track relay. The track relays are shown conventionally by dotted lines and are designated 1T, 2T, 70 etc. The approach signal 1, the entering signal 3, and the absolute starting signal 5 govern east-bound traffic through and past the siding; and the corresponding approach signal 6, entering signal 4, and absolute 75 starting signal 2 govern traffic in the opposite direction. Each of these signals is controlled by a neutral-polar line relay in the usual way, as illustrated for the approach signal 1.

In the accompanying drawing, the invention has been shown applied to the control of the approach signal 1 governing east-bound traffic (left to right) toward the passing siding PS.

Associated with the entering signal 3 is a slow-releasing pole-changer relay 3PC and a special relay 3X. Associated with the signal 5 is a similar pole-changer relay 5PC, and a directional stick relay 5S.

The relays and circuits are shown in the drawing in the normal condition existing when no trains are present in the portion of track under consideration, all the signals indicating clear or proceed.

The line relay 5HD, controlling the signal 5, is normally energized by a circuit in the same way as in my prior patent above mentioned, this circuit being only partially shown and including the front contacts of 100

the track relays 5T and 6T of the track sections next in advance of this signal.

The pole-changer relay 5PC is directly controlled by the line relay 5HD, and is held energized or de-energized when this relay 5HD is respectively energized or de-energized. This energizing circuit for the relay 5PC may be traced on the drawing from (+), indicating a connection to one terminal of a local battery or other source of current, front contact 10 of relay 5HD, wire 11, relay 5PC to (-), indicating the other terminal of said battery.

The line relay 3HD, controlling the signal 3, and the additional special relay 3X are connected in multiple, and are normally energized over a line circuit which may be traced from C (indicating a connection to the usual common return wire of the system), through the front contact 12 of the track relay 3T, line wire 13, front contact 14 of the track relay 4T, wire 15, front contact 16 of relay 5PC, wires 17 and 18, front contact 19 of relay 5PC, wire 20, lower terminal of the battery 21, wire 22, front contact 23 of relay 5PC to C.

This circuit energizes the relay 3HD with the normal polarity and causes the signal 3 to indicate clear or proceed.

With the relays 3HD and 3X both energized, the pole-changer relay 3PC at the signal 3 is energized by a circuit which may be traced from (+), front contact 24 of relay 3X, wire 25, front contact 26 of relay 3HD, wire 27, relay 3PC to (-).

With the pole-changer relay 3PC energized, the line relay 1HD, controlling signal 1, is energized with the normal polarity over a line circuit readily traced on the drawing, and consequently the signal 1 indicates clear or proceed.

Assume that a west-bound train, travelling from right to left, enters the stretch of single track at the right of the passing siding PS. When this train enters this stretch of single track, it causes all of the opposing signals, including the starting signal 5, to indicate stop, through the action of the tumble-down circuits, as explained in detail in my prior patent above mentioned. When a relay 5HD is thus de-energized, to cause the signal 5 to indicate stop, the energizing circuit for the relay 5PC is broken at the front contact 10 of the relay 5HD.

Under these conditions, with the relay 5PC down, the relays 3HD and 3X are energized in multiple over a different circuit, starting at C, through the front contact 12 of the track relay 3T, line wire 13, front contact 14 of track relay 4T, wire 15, back contact 16, wire 22, upper terminal of the battery 21, wire 28, resistance 29, wire 30, back contact 31 of relay 5S, wire 32, back contact 19 of relay 5PC, wire 18, and through the back contact 23 of relay 5PC, to C.

The resistance 29 included in this circuit reduces the current intensity to a value sufficient to energize the relay 3HD effectively to close its contacts, but insufficient to energize the relay 3X effectively. The relay 5PC, being de-energized, reverses the polarity of the current applied to the relay 3HD, thereby causing the signal 3 to indicate caution. The opening of the front contact 24 of the relay 3X breaks the energizing circuit for the relay 3PC; and the de-energization of the relay 3PC reverses the polarity of the current for energizing the circuit 1HD, so that the signal 1 also indicates caution.

Thus, when a west-bound train approaches the siding PS, the starting signal 5 indicates stop, and the approach signal 1 and entering signal 3 also both indicate caution, providing the double distant or caution indication, characteristic of an A. P. B. system, and affording the necessary protection to train movement, as explained in my prior patent above mentioned.

When an east-bound train passes the signal 3, opening the front contact 12 of the track relay 3T and de-energizing the relay 3HD, in so doing, the pole-changer relay 3PC is de-energized, reversing the polarity of the line circuit for the relay 1HD so that the signal 1 indicates caution.

When this east-bound train passes the signal 5, it picks up the directional stick relay 5S in the usual way. The pick-up circuit for the relay 5S may be traced from (+), through the circuit controller 33 operated by the signal 5, wire 34, back contact 35 of track relay 5T, wires 36 and 37, relay 5S to (-). The stick circuit for the relay 5S may be traced from (+), through the back contact 38 of the line relay 5HD, wire 39, front contact 40 of relay 5S, wires 41 and 37, relay 5S to (-). This stick relay 5S is picked up by an east-bound train passing the signal 5, since the back contact 35 of the track relay 5T is closed before the circuit controller 33 of the signal 5 opens, but is not energized for a west-bound train movement, since the circuit controller 33 opens before the track relay back contact 35 is closed, all in a manner familiar to those skilled in the art and explained more in detail in my prior patent above mentioned.

With the directional stick relay 5S energized by such an east-bound train passing the signal 5, the relay 5PC is de-energized the same as for a west-bound train movement, to reverse the polarity of the energizing current for the relays 3HD and 3X; but the resistance 29 is not included in this circuit, being shunted by wire 42, front contact 43 of relay 5S and wire 44, so that the full voltage of the battery 29 is applied to this circuit, and relay 3X, as well as the relay 3HD, is effectively energized. Consequently, the pole-changer relay 3PC remains

energized, and the signal 1 may indicate clear or proceed for a following train the same as in double-track signaling.

The same scheme of control is employed 5 for the approach signal 6.

From the foregoing it can be readily understood how the desired double distant or caution control for an A. P. B. system is attained, without an additional line wire 10 extending the length of the siding. The line circuit for the relay 3HD, in addition to the control of its polarity to govern the caution and proceed indications of the entering signal 3, is also energized with different current values or intensities due to 15 the inclusion and exclusion of the resistance 29, in accordance with the directions of trains approaching and passing the starting signal 5, thereby providing through the medium of the special relay 3X, an extra control for the relay 3PC, which may be utilized to obtain the desired double distant control of the approach signal 1. It will be evident that controlling the current value or intensity 20 of the energizing circuit for the relay 3HD by inserting and cutting out a resistance is only one way of superimposing an additional controlling condition upon this circuit; and it is contemplated that any 25 other suitable means may be adopted for the same purpose.

The particular construction and arrangement of circuits shown and described, represents only one particular embodiment of the 35 invention, and is merely typical or illustrative of the principles, functions, and mode of operation of the invention; and it should be understood that various adaptations, modifications, and additions may be made 40 in this particular arrangement without departing from the scope of the invention.

What I claim is:—

1. In an automatic block signaling system of the type described, two signals governing 45 traffic toward the end of a passing siding, a line circuit, relays energized by said line circuit and responsive to variations in the current intensity for controlling said signals, and means responsive to the direction of 50 movement of trains for controlling the current intensity in said energizing circuit.

2. In a signaling system of the type described, an approach signal, a pole-changer relay governing the indications of said signal, two relays controlling said pole-changer relay and responsive to different current intensities, a line circuit for energizing said two relays, and means for governing both the polarity and current intensity of energi- 60 zation of said line circuit.

3. In a block signaling system of the type described, an entering signal at the entrance to a siding governing traffic toward the siding, an approach signal in the rear of said 65 entering signal governing traffic in the same

direction, a neutral-polar line relay controlling the indications of said entering signal, a line circuit for said relay, means responsive to the direction of movement of trains for energizing said line circuit with currents of different polarity and different intensities, and means controlled over said line circuit and responsive to the intensity of the energization thereof irrespective of its polarity for controlling the indications 75 of said approach signal.

4. In a signaling system of the type described, an approach signal at a distance from the end of a passing siding and governing traffic toward the siding, a line circuit governing the indications of said signal, a pole-changing device for controlling the polarity of energization of said line circuit, and means for governing said device comprising a line circuit extending along 80 the siding and two relays both energized over said line circuit, one of said relays being responsive to the polarity of energization of said line circuit irrespective of its intensity, and the other relay being responsive to the intensity of energization of said line circuit irrespective of its polarity. 90

5. In a signaling system of the type described, an approach signal at a distance from the end of a passing siding and governing traffic toward the siding, a pole-changing device controlling the indications of said signal, a line circuit extending along the siding, a neutral-polar relay energized over said line circuit for controlling said 100 pole-changing device, and means responsive to the intensity of energization of said line circuit irrespective of its polarity for also controlling said pole-changing device.

6. In a block signaling system of the type described, an entering signal at the entrance to a siding governing traffic toward the siding, an approach signal in the rear of said entering signal governing traffic in the same direction, a neutral-polar line relay controlling the indications of said entering signal, a line circuit for said relay, means for energizing said line circuit with current of one or the other polarity depending on track occupancy, a stick relay energized or deenergized in accordance with the direction of movement of a passing train for applying current of a third character to said line circuit when said stick relay is deenergized, and means responsive to said current of a 110 third character for controlling the indications of said approach signal. 115

In testimony whereof I affix my signature.
